UNITED STATES PATENT OFFICE.

CARL R. KLOK, OF CHICAGO, ILLINOIS, ASSIGNOR, BY MESNE ASSIGNMENTS, TO UNITED TABLE-BED COMPANY, A CORPORATION OF VIRGINIA.

FOLDING BED.

1,244,987.

Specification of Letters Patent.

Patented Oct. 30, 1917.

Application filed May 26, 1913. Serial No. 769,839.

To all whom it may concern:

Be it known that I, CARL R. KLOK, a citizen of the United States of America, and resident of Chicago, Cook county, Illinois, have invented a certain new and useful Improvement in Folding Beds, of which the following is a specification.

My invention relates to folding beds in general, but more particularly to beds of this kind which are combined with some other article of furniture, and especially those which are combined with a table or desk or other similar piece of furniture.

Generally stated, the object of my invention is to provide a novel and efficient folding bed of the foregoing general character.

A particular object is to provide an improved construction and arrangement whereby the bed frame, while in folded condition, is movable bodily in a horizontal plane, relative to the table, preliminary to the unfolding of the bed, and also after the bed is fully folded and ready to be inclosed within the table.

Another object is to provide a novel construction whereby the bed and table or other similar structure are separable and capable of use at one and the same time.

It is also an object to provide certain details and features of construction tending to increase the general efficiency and desirability of a table bed of this particular character.

To the foregoing and other useful ends, my invention consists in matters herein disclosed and claimed.

In the accompanying drawings,—

Figure 1, is a sectional view of a table, and also a side elevation of one end portion of the folding bed thereof, embodying the principles of my invention, and showing the said bed in folded condition and ready to be pushed into said table.

Fig. 2, is a side elevation of said bed in unfolded condition.

Fig. 3, is a detail sectional view of one corner portion of the table and bed, being an enlarged section on line 3—3 in Fig. 5.

Fig. 4 is a section on line 4—4 in Fig. 5.

Fig. 5, is a section on line 5—5 in Fig. 4.

As thus illustrated, my invention comprises a table A, provided with a rectangular top a, end walls a¹, and a side wall a², which are all fixed in position at the top of

the table. The four legs a³ are disposed at the corners of the table, in fixed relation thereto, and are of any suitable character. The table top is also provided with a swinging side wall a⁴, hinged to the table top at its upper edge, whereby the box-like upper portion of the table can be opened at one side thereof. The end walls a¹ are provided on the inner surfaces thereof, near their lower edges, with horizontal tracks a⁵, each track being provided with an incline a⁶ at the forward end thereof.

The folding bed B comprises four legs b which are rigidly connected together, and which are disposed at the inner sides of the table legs when the table and bed are brought together, as shown more clearly by Figs. 3 and 5 of the drawings. The bed frame is composed of three sections b¹, b² and b³, the first and last being U-shaped in character, the middle section being composed of two parallel side bars, the entire bed frame being preferably made of angle iron. The sections b¹ and b² are connected together by short links b⁴, and the sections b² and b³ are connected together by similar links b⁵, whereby the said frame, with a suitable metallic fabric stretched thereon, together with the mattress C, are adapted to be folded or rolled up in the manner shown in Fig. 5. Section b¹ is rigidly secured to the tops of the legs b, and the folding legs b⁶ and b⁷ are pivoted respectively to the sections b² and b³, in the manner shown in Fig. 2. In order that the said pivoted legs may automatically fold up, when the frame is folded or rolled up in the manner shown in Fig. 5, the upper ends of the legs b⁶ are connected by links b⁸ with the links b⁴, and the legs b⁷ are similarly connected by links b⁹ with the links b⁵, these links b⁸ and b⁹ being pivoted at opposite ends thereof.

When the bed is folded or rolled up, it rests in compact form upon the tops of the legs b, as shown in Fig. 1, and is then ready to be pushed inside of the table. For this purpose, the said bed is provided at each end thereof with rollers b¹⁰, which travel on the tracks a⁵, whereby the legs b are raised from the floor, by the bodily upward movement of the bed, which raising of the bed is caused by the inclines a⁶, up which latter said rollers are caused to travel. Thus, the bed is supported by the table, when the two

pieces of furniture are brought together, and the bed is practically concealed within the table.

It is obvious, therefore, with the foregoing construction and arrangement that the table and bed are completely separated, when the latter is unfolded, the two being capable of use independently of each other, and at one and the same time. The table, however, as explained, is constructed to support and practically conceal the bed, when the latter is not in use.

An important consideration of my invention is the manner in which both the table and bed are capable, with the construction as shown and described, of conforming to standard requirements in various ways. For example, the bed, when unfolded, is of the right height, that is to say, neither too low nor too high, which latter is often the case when an attempt is made to combine a folding bed with some other piece of furniture. Furthermore, and with the construction shown, the table may be of standard height, rendering it suitable for library or writing purposes, and the clearance below the table top, and below the bed, is of the character required for tables of this kind. In other words, the table and bed are combined without sacrificing any of the standard requirements for either one, the table being of such character that it may be used conveniently for writing purposes, by an adult of average size seated in front thereof. Although the space or clearance below the bottom of the bed is sufficient to render the table suitable for use by the person seated in an ordinary chair, the construction is such that the top of the bed, when it is unfolded, is approximately of the standard height.

With the construction shown the end section b^1 , which may be called the inner end section of the bed-frame, is always rightside-up, and when the frame is folded the other end-section b^3 is rightside-up below the middle section, and the entire weight of the bed when thus folded is sustained by the fixed section b^1 of the frame.

When the bed is in use, the head portion thereof may stand partially within the table, as each guide a^5 a^6 terminates at the inner side of the front legs of the table, so that the legs b of the bed will rest on the floor before the bed frame is entirely withdrawn from the table. In this way, of course, it is not necessary to disturb the top of the table when the bed is withdrawn and unfolded, which is one advantage of this construction, but it will be understood that the bodily movement of the bed frame on a horizontal plane can be employed for any suitable or desired purpose, and in conjunction with a table having any suitable or desired construction. Each of the three sections of the bed frame is approximately one-third of the

length of the bed, and when the bed frame is folded within the table, the latter is then in condition for use in the ordinary manner, and, with the bed frame of the standard or ordinary length, the table will be of such width that it can be moved around and pushed through doorways of the ordinary or usual width. Obviously, the bed frame can be of any suitable or desired width, as the bed frame folds into three superimposed layers, so that the table as stated, may be of a width to pass through an ordinary doorway, and the table can, therefore, be of any suitable or desired length, and can be of such length that the bed will be of full width, like an ordinary full sized double bed, without departing from the ordinary dimensions or proportions usually required for tables. While one end of the bed is partially within the table, the front wall a^4 of the table can be lowered to rest in an inclined position upon the end portion of the bed, and in this way the table will form the head of the bed. As it is not necessary to have the table top a removable, it follows that the construction of the table can be rendered stiff and rigid by the permanent fastening of this table-top in place, so that the two opposite ends of the table are rigidly and firmly connected together and held against spreading apart. Of course, though, when the bed is entirely withdrawn from the table, so that the legs b rest upon the floor, there is then no weight imposed on the bed by the table, so that the structure of the latter is then under no strain. Obviously, therefore, the invention affords a novel and practical method of combining a table with a folding bed frame of this kind, and is intended to solve some of the various problems involved in combining a table and bed into one unitary article of furniture, but the invention is not, of course, limited to the exact construction shown and described.

What I claim as my invention is:

1. A table bed comprising a table, and a folding bed removably supported by means within the upper portion of said table, adapted to be disconnected therefrom and unfolded for use, provided with separate legs upon which the entire bed rests when fully folded and while being moved toward the table.

2. A table bed comprising a table, and a folding bed in said table, adapted to be disconnected therefrom and unfolded for use, provided with separate legs upon which the bed rests while being moved toward the table, and means concealed within the upper portion of the table for raising the bed and thereby lifting the legs off the floor.

3. A table bed comprising a table, and a folding bed in said table, adapted to be disconnected therefrom and unfolded for use, provided with separate legs upon which the

- bed rests while being moved into the table, and tracks concealed within the upper portion of the table for raising the bed and thereby lifting the legs off the floor.
5. A table bed comprising a table, and a folding bed in said table, adapted to be disconnected therefrom and unfolded for use, provided with separate legs upon which the bed rests while being moved toward the table, said bed legs being disposed against the table legs when the bed is within the table.
10. In combination, a body having a top adapted for supporting loose articles thereon, and a folding bed frame inclosed in said body below said top and movable bodily into position for unfolding while said top remains in horizontal position, said movement of the frame while folded being in the same direction thereof in which the bed is thereafter unfolded, and said frame having laterally projecting means for engaging the upper portion of said body to support the bed when the folded bed frame is moved bodily in the opposite direction. 70
15. A table provided with a fixed top, and a folding bed frame below said top, adapted to be moved outward bodily and then unfolded while said top remains in the horizontal plane thereof, means on the upper end portion of the table to support the folded bed frame for movement bodily in the direction in which the same unfolds, and folding legs for supporting the bed frame on the floor, said bed frame when entirely folded being movable bodily into said table. 75
20. In combination, a body having a fixed top adapted for supporting loose articles thereon, and a folding bed frame inclosed in said body below said top and movable bodily into position for unfolding while said top remains in horizontal position, said movement of the frame while folded being in the same direction thereof in which the bed is thereafter unfolded, and said frame having laterally projecting means for engaging the upper portion of said body to support the bed when the folded bed frame is moved bodily in the opposite direction. 80
25. A table provided with a top, a folding bed below said top, adapted to be unfolded while said top remains in the horizontal plane thereof, provided with folding legs for supporting the middle and one end of the bed, said folding bed also having four fixed legs upon which the other end of the bed is supported when in use and while being folded, and means above the fixed legs to support the bed in the table. 85
30. In combination, a body having a fixed top adapted for supporting loose articles thereon, and a folding bed frame inclosed in said body below said top and movable bodily into position for unfolding while said top remains in horizontal position, said movement of the frame while folded being in the same direction thereof in which the bed is thereafter unfolded, and said frame having laterally projecting means for engaging the upper portion of said body to support the bed when the folded bed frame is moved bodily in the opposite direction. 90
35. A table provided with a top, and a folding bed below said top, adapted to be unfolded while said top remains in the horizontal plane thereof, provided with folding legs for supporting the bed, the said top having four fixed legs, and said bed having four fixed legs, said table having means concealed in the upper portion thereof for raising the bed therein. 95
40. In combination, a body having a fixed top adapted for supporting loose articles thereon, and a folding bed in said body, movable into position for use while said top remains in horizontal position, said top being fixed to said body, and said bed being movable bodily in folded condition from below said top to permit unfolding thereof, said bed including a frame composed of pivotally connected links and sections, said links providing space for the bedding between the sections when the frame is folded, and one end section being permanently right side up and having a sliding connection with said body. 100
45. A table provided with a top, and a folding bed below said top, adapted to be unfolded while said top remains in the horizontal plane thereof, provided with folding legs for supporting the bed, end walls for the table, tracks on said end walls, means for engaging said tracks when the folded bed is moved into the table, and legs supported by said bed when said means engage said tracks. 105
50. In combination, a body, a folding bed frame in said body, movable relative thereto in folded condition, preliminary to being unfolded, adapted to be unfolded for use after said preliminary movement, and means to hold the bed frame against sidewise displacement during said movement, said frame including sections which are horizontal when inclosed in said body, and one of which sections is permanently right side up, 110
55. A table provided with a top, and a folding bed below said top, adapted to be unfolded while said top remains in the horizontal plane thereof, provided with folding legs for supporting the bed, end walls for the table, tracks on said end walls, means for engaging said tracks when the folded bed is moved into the table, and legs supported by said bed when said means engage said tracks. 115
60. In combination, a body having ends, a folding bed in said body, movable relative thereto in folded condition between said ends, preliminary to being unfolded, adapted to be unfolded for use after said preliminary movement, said bed including a frame composed of pivotally connected sections, the inner end section being permanently 120
65. A table provided with a top, and a folding bed below said top, adapted to be unfolded while said top remains in the horizontal plane thereof, provided with folding legs for supporting the bed, end walls for the table, tracks on said end walls, means for engaging said tracks when the folded bed is moved into the table, and legs supported by said bed when said means engage said tracks. 125
70. In combination, a body having ends, a folding bed in said body, movable relative thereto in folded condition between said ends, preliminary to being unfolded, adapted to be unfolded for use after said preliminary movement, said bed including a frame composed of pivotally connected sections, the inner end section being permanently 130

- right side up and having a direct sliding connection with the ends of said body, and legs supported by said inner end section when the bed is folded.
15. In combination, a body having a box-like upper portion, a folding bed in said body, movable relative thereto without disturbing the folded condition thereof, preliminary to being unfolded, adapted to be unfolded for use after said preliminary movement, said bed including a frame composed of pivotally connected links and sections, said links providing space for the bedding between the sections when the bed is folded, and the upper portion of said body having tracks to support the bed in said folded condition for said preliminary movement, and to receive the bed when entirely folded.
16. In combination, a body, a folding bed frame in said body, movable relative thereto in folded condition, preliminary to any unfolding thereof, adapted to be unfolded for use after said preliminary movement, means at opposite sides of the bed to hold the frame against sidewise displacement during said preliminary movement, legs supported by said frame when the bed is folded, and folding legs to support the frame on the floor when the bed is unfolded, said preliminary movement being sufficient to carry the folded bed frame bodily and without any unfolding thereof into an exposed position at the front of said body.
17. In combination, a body, a folding bed frame in said body, movable relative thereto in folded condition, preliminary to any unfolding thereof, adapted to be unfolded for use after said preliminary movement, means at opposite sides of the bed to hold the frame against sidewise displacement during said preliminary movement, and folding legs to support the frame on the floor when the bed is unfolded, said preliminary movement being sufficient to carry the folded bed frame bodily and without any unfolding thereof into an exposed position at the front of said body, said frame having outer folding sections and an inner end section which slides horizontally into and out of said body while said top remains in horizontal position, said body having a table top, and said sliding end sections supporting the entire weight of the bed when said frame is folded and pushed into the body.
18. In combination, a body, a folding bed frame in said body, movable relative thereto in folded condition, preliminary to any unfolding thereof, adapted to be unfolded for use after said preliminary movement, means at opposite sides of the bed to hold the frame against sidewise displacement during said preliminary movement, legs supported by said frame when the bed is folded, and folding legs to support the frame on the floor when the bed is unfolded, said preliminary movement being sufficient to carry the folded bed frame bodily and without any unfolding thereof into an exposed position at the front of said body, said frame having outer folding sections and an inner end section which slides horizontally into and out of said body while said top remains in horizontal position, said body having a table top, and said sliding end sections supporting the entire weight of the bed when said frame is folded and pushed into the body.
19. A folding bed comprising a furniture body having permanent ends and a fixed top, a three-section folding bed frame whereof the inner end-section thereof is always right side up and horizontal, having devices to connect the sections together, means on the ends of said body adjacent the frame to support the sides of said body permanently right side up inner end section for sliding movement into and out of said body, while the frame is entirely folded, means to support said inner end section stationary while the other sections are being folded thereon to bring the outer end section right side up below the middle section, folding legs to support the middle and outer end sections on the floor, the frame being practically entirely outside of said body when the bed is unfolded, thereby permitting the use of said middle section as a seat for entering and leaving the bed, and means on said frame to support a mattress, said sections being each approximately one-third the length of the bed, the outer end section and the middle section being supported entirely by and horizontally above the said sliding inner end section when the bed is entirely folded, and means for closing the front of said body to conceal the folded bed below said top.
20. A folding bed comprising a furniture body having permanent ends and a fixed top, a three-section folding bed frame whereof the inner end section thereof is always right side up and horizontal, having devices to connect the sections together, means on the ends of said body adjacent the frame to support the sides of said body permanently right side up inner end section for sliding movement into and out of said body, while the frame is entirely folded, means to support said inner end section stationary on the floor while the other sections are being folded thereon to bring the outer end section right side up below the middle section, folding legs to support the middle and outer end sections on the floor, the frame being practically entirely outside of said body when the bed is unfolded, thereby permitting the use of said middle section as a seat for entering and leaving the bed, and means on said frame to support a mattress, said sections being each approximately one-third the length of the bed, the outer end section being supported entirely by and horizontally above the said sliding inner end section when the bed is entirely folded, and means for closing the front of said body to conceal the folded bed below said top.

the folded bed below said top, said devices including links which stand upright at front and rear of said body when the bed is folded.

5 21. A table-bed comprising a table-body having fixed end walls and a fixed rear side wall, a fixed top and a movable front side wall, a folding bed frame, means adjacent the sides of the bed to support the 10 sides of one end section of said frame in sliding connection with upper portions of said body, thereby to permit movement of the folded frame bodily into and out of said body, which end section is horizontal 15 when the bed is folded, said end walls extending approximately a third of the length of the bed, and legs for said frame, said body having four fixed legs, and said movable front side wall being mounted to close 20 after the folded frame is moved bodily within the table.

22. A folding bed comprising a body, a folding bed frame having means at opposite sides thereof to slide horizontally on said 25 body, in the direction in which the bed unfolds, preliminary to any unfolding thereof, and which frame is foldable to bring the mattress and bedding entirely inside the rectangular bundle formed thereby, legs supported by said frame when the bed is folded, folding legs extending below the horizontal plane of said means to support said frame, and a top adapted to conceal the bed 30 within said body and form with the latter an ordinary table.

35 23. A folding bed comprising a body, a folding bed frame having means at opposite sides thereof to slide horizontally on said

body, in the direction in which the bed unfolds, preliminary to any unfolding thereof, 40 and which frame is foldable to bring the mattress and bedding entirely inside the rectangular bundle formed thereby, folding legs extending below the horizontal plane of said means to support said frame, and a top 45 adapted to conceal the bed within said body and form with the latter an ordinary table, said body having guides, said frame having pivotally connected sections one of which slides on said guides, and the other 50 sections of the frame being manually operable to fold and unfold the bed before and after the horizontal movement thereof.

24. A folding bed comprising a body, a folding bed frame having means at opposite 55 sides thereof to slide horizontally on said body, in the direction in which the bed unfolds, preliminary to any unfolding thereof, and which frame is foldable to bring the mattress and bedding entirely inside the 60 rectangular bundle formed thereby, legs supported by said frame when the bed is folded, folding legs extending below the horizontal plane of said means to support said frame, and a top adapted to conceal the bed 65 within said body and form with the latter an ordinary table, said body having four fixed legs to support the folded bed within the table, fixed end and side walls rigid with said table legs, and a movable 70 front wall.

Signed by me this 17th day of May, 1913.
